PROCESS OF REFINING PETROLEUM OIL

Filed April 1, 1940

UNITED STATES PATENT OFFICE

2,260,620

PROCESS OF REFINING PETROLEUM OIL

William T. Hancock, Long Beach, Calif.

Application April 1, 1940, Serial No. 327,198

8 Claims. (Cl. 196—147)

This invention has to do with the refining of petroleum oils, and has for its general object to provide a combined treating and cracking system whereby the cracking plant charging stock is employed in the treatment of pressure distillate produced by such plant, all in a manner to enable impurities removed from the distillate to be converted to desirable and recoverable fractions in the cracking plant, and to effect final removal from the system of sulphur-containing and other compounds from which it is desired to free the distillate prior to treatment.

The pressure distillate treating system employed is the general type described in Patent No. 2,162,715 issued to me on Process for refining cracked petroleum distillate. According to this system, heated pressure distillate is subjected to polymerization by contacting it with fuller's earth or other adsorptive clays, and the polymerized distillate then is mixed with heated higher boiling oil which has a solvent affinity for gum-forming and sulphur-containing impurities of the distillate. The gasoline content of the distillate then is vaporized from the solvent oil, leaving the impurities in the latter. One of my primary objects is to enable such solvent oil to be used as cracking plant charging stock according to a method that will subject hydrocarbons removed from the pressure distillate to reconversion, and accomplish the removal in or beyond the cracking system of undesirable impurities, principally sulphur compounds, from the pressure distillate to be sent to the treating system. This feature also is dealt with in my copending application Ser. No. 306,347, filed November 27, 1939, on System for refining petroleum oils, which discloses a process in which the solvent oil is used as cracking stock.

In accordance with the present process, pressure distillate freed from fixed or uncondensable sulphur gases, is subjected to polymerization, then admixed with a heated higher boiling solvent oil, such as fuel oil. The gasoline content of the distillate subsequently is vaporized from the solvent oil and then condensed. All or a portion of the solvent oil, containing impurities removed from the pressure distillate, is supplied as charging stock to a cracking plant of suitable type and operation, in which the charging stock undergoes conversion to produce gasoline-containing pressure distillate, and usually an unvaporized heavy residue which is removed from the system. In this manner, hydrocarbons removed from the pressure distillate by the solvent oil in the treating stage, are subjected to recon-

version and recovery as desirable fractions in the cracking plant, and undesirable or non-recoverable impurities are removed from the system in the cracking plant residue.

5 The principal impurity removed in the cracking plant is sulphur which may have been retained in various combined forms by the solvent oil, and which is converted by the cracking operation to fixed gases. These gases, in turn, are 10 removed in the usual manner as the cracking plant tail gases, and preferably also by subjecting the pressure distillate to a stabilizing or like treatment for the final isolation of acid gases that may remain in the distillate after its condensation in the cracking plant.

15 The invention also provides a system for two-stage treatment of the distillate by first contacting it with adsorptive material and solvent oil as hereinabove explained, and then again subjecting the first treated distillate or its gasoline fraction to polymerization and admixture with higher boiling solvent oil. This last mentioned solvent oil has a higher boiling range than the gasoline content of the distillate being treated, but preferably lower than the boiling range of the solvent oil employed in the first stage treatment. Preferably, gas oil is used as the second stage solvent oil, and after separation from the gasoline fraction of the distillate, is sent to a 20 gas oil cracking plant operating to produce pressure distillate and to remove impurities in the same general manner as the fuel oil cracking plant. The pressure distillates produced in the two cracking plants may be combined and subjected to treatment for the removal of impurities, 25 all in the manner generally explained and as will hereinafter more fully appear.

30 The invention will be more fully understood from the following description of a typical and 40 illustrative system representing a preferred embodiment of the invention. The description refers to the accompanying drawing illustrating the system diagrammatically and in flow sheet form.

45 Referring to the drawing, the system may be described starting with the polymerizing treatment given the pressure distillate from the cracking units and after removal of sulphur-containing gases, all as will hereinafter appear. The 50 distillate is taken from a suitable source, such as storage conventionally illustrated by the tank 10, through line 11 to be pumped through a heater 12 in which the oil is heated to proper polymerizing temperature in excess of 200° F., and ordinarily in the neighborhood of 350° F.

Leaving heater 12 the distillate is discharged through line 13 into clay tower 14 wherein the distillate is subjected to polymerization by flowing through and intimately contacting a body of adsorptive material 15, such as the clays heretofore mentioned, within the tower. It will be understood that the path of contact between the distillate and adsorptive material may be lengthened as desired by using a single clay column of considerable height, or a plurality of series-connected clay columns.

A suitable solvent oil having a boiling range substantially higher than that of the gasoline content of the distillate, is introduced to the system through line 16. The solvent oil used consists of a suitable cracking stock and where, as in the illustrated system, the invention is adapted to subsequent or second stage polymerization of the distillate followed by solvent oil treatment of the distillate, the solvent oil introduced through line 16 preferably is of a type having a higher boiling range than the solvent oil used in the second stage treatment. Typically, raw fuel oil may be introduced through line 16 and discharged by pump 17 through a heater 18 wherein the oil is heated to a temperature of around 500° F. to 575° F., and discharged through line 19 to a receiver 20 wherein the heated solvent oil is intimately comingled with the polymerized pressure distillate flowing from the clay tower 14 through line 21. Ordinarily it is preferred to admix the two oils in approximately the proportions of from three to four parts of the solvent oil to one part of the pressure distillate. Instead of mixing the oils beyond the fuel oil heater as described, the polymerized distillate may be taken through line 22 to be mixed with the fuel oil in line 16, and the two oils then heated together to a temperature of from 350° F. to 475° F. or above.

The mixed oils are discharged through line 23 to a suitable vaporizing zone, for example the bottom chamber 24 of the dephlegmator 25, within which the gasoline content of the distillate vaporizes and separates from the solvent oil, leaving gum-forming and sulphur-containing compounds of the distillate remaining in the unvaporized solvent oil. The heat supplied to the pressure distillate by the solvent oil, or by passage of the mixed oils through heater 18, may and preferably will be sufficient to cause vaporization and separation of the entire gasoline fraction from the solvent oil within dephlegmator 25. However, where the temperature of the mixed oils introduced to the dephlegmator may not be sufficient to vaporize all of the gasoline, additional heat may be supplied as by means of the steam coil 26 in the bottom of chamber 24 within which the unvaporized oil collects.

The solvent oil, containing impurities removed from the pressure distillate, may be taken directly from the base of dephlegmator 25 through line 27 to be discharged via line 28 to the fuel oil cracking plant, or provision may be made for recirculating a portion of the solvent oil from the dephlegmator to the heater 18, thereby maintaining a greater rate of solvent oil flow to be mixed with the pressure distillate than the rate at which the oil is being supplied to the system through line 16. As a typical recirculating system, the solvent oil may be discharged through line 27 into accumulator 29, from an upper location in which a portion of the oil is taken through line 30 to be combined at the proportioning valve 31 with the fuel oil in line 16. The accumulator

is of sufficient volume to permit gravitation of heavier bodies to the bottom, from which the remaining portion of the solvent oil is withdrawn through line 28 to be fed to the cracking unit.

Leaving the dephlegmator 25, through line 32, the gasoline vapors may suitably be subjected to condensation as by a condenser 33 from which the condensate is collected in receiver 34. The condensate then is forced by pump 35 through line 36 to heater 37 wherein the oil is heated to around 350° F. for second stage polymerization. The heated distillate flows through line 38 to clay tower 39 to be contacted with adsorptive material 40, as previously described with reference to clay tower 14. Back pressure sufficient to keep the distillate in liquid phase while contacting the adsorptive material may be maintained by valve 41 in line 42, or by valve 43 in line 44 beyond the mixer 45. Similar back pressure may be maintained on the distillate flowing through clay tower 14, by valve 46 or valve 47. While it is desirable that in both stages the distillate be maintained in liquid phase while contacting the clay, it is to be understood that the distillate and the solvent oil may be mixed under any desired pressure which may or may not be such as to maintain the gasoline content of the distillate in liquid phase in advance of the vaporizing zone.

A relatively low boiling charging stock, such as gas oil, is introduced to the system through line 48 and is discharged by pump 49, with or without distillate taken from the clay tower through line 50, to a heater 51 wherein the oil is heated to a temperature that may correspond substantially to the temperature at which the fuel oil is heated in heater 18, as previously described. Also, the gas oil is mixed with the polymerized distillate in substantially the same proportions as before. The mixed oils are discharged through line 44 into a vaporizing zone 52 in a second dephlegmator 53, from the base of which the unvaporized solvent oil passes through line 54 to an accumulator 55. Again, all the oil may be taken from the accumulator to be discharged by pump 56 through line 57 to the gas oil cracking unit, or a portion of the oil may be recirculated through line 58 and the proportioning valve 59 to the heater 51. The vapors leaving dephlegmator 53 through line 60 may be passed through clay tower 61 to remove any remaining gum-forming or color-producing constituents, and then discharged through line 62 to fractionating column 63 for the removal of higher boiling ends that are condensed and withdrawn through line 64. The gasoline vapors pass through line 65 to condenser 66, and the product condensate is collected in a final receiver 67.

The solvent fuel oil withdrawn from accumulator 29 through line 28 is pumped to a fuel oil cracking unit, generally indicated at 68, and the gas oil being withdrawn from accumulator 55 through line 57 similarly is pumped to the gas oil cracking unit generally indicated at 69. Both solvent oils in the accumulators are of course heated, ordinarily to temperatures above 375° F. and thus provide preheated charging stocks for the cracking units. It will be understood that these cracking units 68 and 69 may be of any suitable type adapted to convert their respective charging stocks to pressure distillate, and therefore that the illustrated cracking units should be regarded as typical and illustrative only. The fuel oil cracking unit is shown to comprise a still 70 in which the charging stock is subjected

to cracking under the usual temperatures and pressures, for example 930° F. at 500 lbs. per sq. in., from which the cracked hydrocarbons are discharged through line 71 to a reaction and separating chamber 72. Beyond valve 71a the pressure may be reduced to about 250 lbs. per sq. in. in the reaction chamber. The unvaporized residue, which may contain impurities removed from the pressure distillate by the solvent oil still charging stock, as previously explained, is withdrawn from the separator and removed from the system through the valved line 73. The vapors leaving the separator through line 74 are subjected to fractionation in one or more dephlegmators 75 to condense heavy ends removed through line 76, and the vapors are passed through line 77 to condenser 78 from which the gasoline-containing pressure distillate collects in receiver 79.

The illustrated gas oil cracking unit 69 is similar to the described fuel oil cracking unit, and the corresponding parts have been given the same reference numerals. In the gas oil cracking still, the charging stock may be subjected to cracking at somewhat higher temperatures and pressure, for example at around 950° F. and 600 lbs. per sq. in., with a pressure of around 400 lbs. per sq. in. maintained in the reaction chamber. While the gas oil introduced to the system through line 48 may be taken from any suitable source, I prefer to utilize for the purposes of this solvent oil, the heated gas oil produced in the cracking plants, together with any additional make-up required, such as gas oil from a straight run plant (not shown) introduced through line 48a. Accordingly, the gas oil condensates from the bottoms of dephlegmators 75 are shown to be delivered through lines 91 and 92 (and an accumulator 93 if desired) to the gas oil heater inlet line 48.

Uncondensable vapors together with some sulphur-containing and other fixed gases are removed through the valved lines 81 and 82 and taken through line 83 for further treatment or disposition, as may be desired. The pressure distillates from both receivers 79 may be further treated by any suitable method for removal of sulphur-containing gases, in order that the distillate as supplied to the treating system may be as free as possible of unnecessary contamination. To illustrate a typical method, the distillate from receiver 79 is withdrawn through lines 83a and 84 and passed through line 85 to a heater 86 wherein the temperature of the distillate is raised sufficiently, e. g. 300° F., to permit vaporization of light ends and sulphur containing gases in the usual type of pressure distillate stabilizing plant. The latter is shown conventionally as comprising one or more dephlegmators or fractionating columns 87 to which the heated distillate is supplied from line 88, the vapors and gases being removed through line 89 to be disposed of, if desired, with the fixed gases taken from the cracking units through line 83. The stabilized pressure distillate is taken through line 90 to storage 10, thereafter to be given the combined clay and solvent oil treatments for the removal of impurities.

I claim:

1. The process of refining petroleum oils that includes, subjecting separate oil streams to cracking in separate cracking zones, subjecting the hydrocarbons from said cracking zones to fractionation and condensation to produce gasoline-containing pressure distillate, subjecting said distillate, while heated, to polymerization

5 by contacting it with adsorptive material, passing through a heating zone a stream of solvent oil having a boiling range substantially higher than that of the gasoline content of the pressure distillate, mixing the heated solvent oil with the polymerized pressure distillate, vaporizing and separating the gasoline from the unvaporized solvent oil in a vaporizing zone, condensing the vapors to produce a gasoline-containing condensate, passing unvaporized solvent oil from the vaporizing zone to one of said cracking zones as 10 charging stock, heating said condensate and contacting it with adsorptive clay, then mixing said condensate with heated oil having a higher boiling range than the gasoline content of the condensate, vaporizing and separating the vapors from the higher boiling oil, subjecting the separated vapors to condensation, and passing the unvaporized solvent oil to the other of said cracking zones as charging stock.

2. The process of refining petroleum oils that includes, subjecting relatively high boiling and low boiling oils to cracking in separate cracking zones, subjecting the hydrocarbons from said cracking zones to fractionation and condensation to produce gasoline-containing pressure distillate, subjecting said distillate, while heated, to polymerization by contacting it with adsorptive material, passing through a heating zone a stream of solvent oil having a boiling range substantially higher than that of the gasoline content of the pressure distillate, mixing the heated solvent oil with the polymerized pressure distillate, vaporizing and separating the gasoline from the unvaporized solvent oil in a vaporizing zone, condensing the vapors to produce a gasoline-containing condensate, passing unvaporized solvent oil from the vaporizing zone to one of said cracking zones as 15 the higher boiling charging stock, heating said condensate and contacting it with adsorptive clay, then mixing said condensate with heated oil having a higher boiling range than the gasoline content of the condensate, vaporizing and separating the vapors from the higher boiling oil, subjecting the separated vapors to condensation, and passing the unvaporized solvent oil to the other of said cracking zones as charging stock.

3. The process of refining petroleum oils that includes, subjecting separate oil streams to cracking in separate cracking zones, subjecting the hydrocarbons from said cracking zones to fractionation and condensation to produce gasoline-containing pressure distillate, heating said distillate to a temperature in excess of about 200° F. and subjecting the heated distillate to polymerization by contacting it with adsorptive material, passing through a heating zone a stream of solvent oil having a boiling range substantially higher than that of the gasoline content of the pressure distillate, mixing the heated solvent oil with the polymerized pressure distillate, vaporizing and separating the gasoline from the unvaporized solvent oil in a vaporizing zone, condensing the vapors to produce a gasoline-containing condensate, passing unvaporized solvent oil from the vaporizing zone to one of said cracking zones as 20 charging stock, heating said condensate and contacting it with adsorptive clay, then mixing said condensate with heated oil having a higher boiling range than the gasoline content of the condensate, vaporizing and separating the vapors from the higher boiling oil, subjecting the separated vapors to condensation, and passing the unvaporized solvent oil to the other of said cracking zones as the lower boiling charging stock.

4. The process of refining petroleum oils that

unvaporized solvent oil to the other of said cracking zones as charging stock.

4. The process of refining petroleum oils that includes, subjecting separate oil streams to cracking in separate cracking zones, subjecting the hydrocarbons from said cracking zones to fractionation and condensation to produce gasoline-containing pressure distillate, removing sulphur-containing gases from the distillate, subjecting said distillate, while heated, to polymerization by contacting it with adsorptive material, passing through a heating zone a stream of solvent oil having a boiling range substantially higher than that of the gasoline content of the pressure distillate, mixing the heated solvent oil with the polymerized pressure distillate, vaporizing and separating the gasoline from the unvaporized solvent oil in a vaporizing zone, condensing the vapors to produce a gasoline-containing condensate, passing unvaporized solvent oil from the vaporizing zone to one of said cracking zones as charging stock, heating said condensate and contacting it with adsorptive clay, then mixing said condensate with heated solvent oil having a higher boiling range than the gasoline content of the condensate, vaporizing and separating the vapors from said solvent oil, subjecting the separated vapors to condensation, and passing the unvaporized solvent oil to the other of said cracking zones as charging stock.

5. The process of refining petroleum oils that includes, subjecting relatively high boiling and low boiling oils to cracking in separate cracking zones, subjecting the hydrocarbons from said cracking zones to fractionation and condensation to produce gasoline-containing pressure distillate, removing sulphur-containing gases from the distillate, subjecting said distillate, while heated, to polymerization by contacting it with adsorptive material, passing through a heating zone a stream of solvent oil having a boiling range substantially higher than that of the gasoline content of the pressure distillate, mixing the heated solvent oil with the polymerized pressure distillate, vaporizing and separating the gasoline from the unvaporized solvent oil in a vaporizing zone, condensing the vapors to produce a gasoline-containing condensate, passing unvaporized solvent oil from the vaporizing zone to one of said cracking zones as the higher boiling charging stock, heating said condensate and contacting it with adsorptive clay, then mixing said condensate with heated oil having a higher boiling range than the gasoline content of the condensate but a lower boiling range than the first mentioned solvent oil, vaporizing and separating the vapors from the higher boiling oil, subjecting the separated vapors to condensation, and passing the unvaporized solvent oil to the other of said cracking zones as the lower boiling charging stock.

6. The process of refining petroleum oils that includes, subjecting relatively high boiling and low boiling oils to cracking in separate cracking zones, subjecting the hydrocarbons from said cracking zones to fractionation and condensation to produce gasoline-containing pressure distil-

late, contacting the distillate, while heated, with adsorptive material, then mixing the distillate with a higher boiling range heated solvent oil, vaporizing the gasoline content of the distillate from the solvent oil and cooling the vapors to produce condensate, passing the separated solvent oil to one of said cracking zones as the higher boiling charging stock, heating and contacting said condensate with adsorptive material, then mixing the condensate with a heated solvent oil having a boiling range higher than the gasoline content of the condensate but lower than that of the first mentioned solvent oil, vaporizing the gasoline from the mixed oils, and passing the unvaporized solvent oil to the other of said cracking zones as the lower boiling charging stock.

7. The process of refining petroleum oil that includes, subjecting the oil to cracking in a cracking zone, subjecting the hydrocarbons from said cracking zone to fractionation to produce relatively heavy residuum, gasoline-containing pressure distillate, and uncondensed gases, subjecting the distillate, while heated, to polymerization by contacting it with adsorptive material, passing through a heating zone a stream of solvent oil having a boiling range substantially higher than that of the gasoline content of the pressure distillate, mixing the heated solvent oil with the polymerized pressure distillate, vaporizing and separating the gasoline from the unvaporized solvent oil in a vaporizing zone, thereby leaving gum-forming and sulphur-containing impurities of the distillate in said solvent oil, recirculating a portion of the solvent oil from the vaporizing zone to again be mixed with the polymerized pressure distillate, and passing another portion of said solvent oil from the vaporizing zone to said cracking zone as preheated charging stock.

8. The process of refining petroleum oil that includes, subjecting the oil to cracking in a cracking zone, subjecting the hydrocarbons from said cracking zone to fractionation to produce relatively heavy residuum, gasoline-containing pressure distillate, and uncondensed gases, subjecting the distillate, while heated, to polymerization by contacting it with adsorptive material, passing through a heating zone a stream of solvent oil having a boiling range substantially higher than that of the gasoline content of the pressure distillate, mixing the heated solvent oil with the polymerized pressure distillate, vaporizing and separating the gasoline from the unvaporized solvent oil in a vaporizing zone, thereby leaving gum-forming and sulphur-containing impurities of the distillate in said solvent oil, passing the heated unvaporized solvent oil from the vaporizing zone into an enlarged accumulator zone, recirculating a portion of the solvent oil from said accumulator zone through said heating zone to again be mixed with the polymerized pressure distillate, and passing another portion of said solvent oil from the accumulator zone to said cracking zone as preheated charging stock.

WILLIAM T. HANCOCK.
